UNITED STATES PATENT OFFICE.

JAMES N. WILSON, OF HIGGINSVILLE, MISSOURI, ASSIGNOR TO HIMSELF
AND JAMES H. CAMPBELL, OF SAME PLACE.

PULLEY-BELTER.

SPECIFICATION forming part of Letters Patent No. 298,929, dated May 20, 1884.

Application filed March 28, 1884. (No model.)

To all whom it may concern:

Be it known that I, JAMES N. WILSON, of Higginsville, in the county of Lafayette and State of Missouri, have invented a new and 5 Improved Pulley-Belter, of which the following is a full, clear, and exact description.

My invention consists of an adjustable clamp device of novel contrivance adapted to clamp on a driving-pulley across the face and 10 for running the belt on the pulley, the said belter being designed for running on the driving-belts of thrashing-machines and other machines, which are apt to run off in consequence of being long and crooked and running at 15 high speed, all as hereinafter fully described.

Reference is to be had to the accompanying drawings, forming part of this specification, in which similar letters of reference indicate corresponding parts in all the figures.

20 Figure 1 is a top view of my improved pulley-belter. Fig. 2 is a side elevation; and Figs. 3 and 4 are transverse sections, looking in opposite directions, on the line xx of Fig. 2.

I make an extension-clamp consisting of 25 jaw a , attached to the end of a bar, b , fitted to slide lengthwise in another bar, c , having a jaw, d , attached to it, and connect bar b to an adjusting-screw, e , by a screw-tapped cross bar or plate, f , said screw being capable of 30 sliding lengthwise a short distance, and having a cam-lever, g , pivoted to the end, extending out through the bearing h in the end of bar c , for revolving said screw, and also for drawing it lengthwise to tighten the clamp.

35 A coiled spring, i , is fitted on the screw between the collar j and the washer l , to shift the screw back when released by the cam-lever. The jaw d is also adjustable along the bar c to be secured at any point by means of 40 binding-screws k , which will in practice be in the form of hand-screws for convenience, and may be screwed into holes l , made for them at suitable intervals along the sides of bar c . On the side opposite to the jaws a d , which may

45 be hooked, as shown, the bars b c each have a flange, m , said flanges being at the respective extremities of the clamp. For using the clamp to run a driving-belt onto a pulley, the jaw d is first adjusted according to the width of the 50 face of the pulley, so that when the clamp is placed across the face of the pulley-rim represented in section in dotted lines n , Fig. 2, the hooks a d will hook around the edges of

the rim. The hooks are then drawn up tight by the lever g to clamp the belter fast to the 55 edges of the pulley. The belt o , dotted Fig. 2, is then placed over the flange m of that end of the clamp that projects to the side of the pulley from which the belt is to be run onto said pulley. Then the pulley is turned in the 60 proper direction for running the belt on, which accomplishes the belting in the same manner as when the belt is held partly on the face of the pulley by hand, while the pulley is slowly turned, the belter being a means of holding 65 the belt more effectually, and so as to avoid the severe and dangerous operations of holding by hand, particularly in the case of strong and heavy belts. When the belt has run on the pulley, the belter will escape from under 70 the belt into the open space between the two ranges of the belt, where it can be quickly detached by shifting the lever g to release the clamp and lifting it off the pulley. This can be done without stopping the pulley in the 75 case of such large machinery as makes it desirable to turn the pulley slowly by the driving-engine.

The jaws may be adjusted to the size of the pulley-rim by the screw e entirely within a 80 certain range; but for wider ranges the jaw d is also to be shifted.

The form of the jaws a d represented in the drawings is best adapted for metal pulleys; but I propose to make the jaws with flat and 85 roughened surfaces suitable for firmly gripping the sides of wooden pulleys when required.

Having thus described my invention, I claim as new and desire to secure by Letters Patent— 90

1. The improved pulley-belter, consisting of the extensible clamp a b c d , adjusting-screw e , and the flanges m , combined and arranged substantially as described.

2. The combination of the extensible clamp 95 a b c d , adjusting-screw e , and the clamping-lever g , substantially as described.

3. The adjusting-screw e and clamping-lever g , in combination with the extensible clamp a b c d , said screw being fitted to slide in the 100 bearing h , and having the reacting-spring i , substantially as described.

JAMES N. WILSON.
